UNITED STATES PATENT OFFICE.

WILLIAM EDWARD SEELYE, OF BRAINERD, MINNESOTA.

COMBINATION-TOOL.

SPECIFICATION forming part of Letters Patent No. 660,204, dated October 23, 1900.

Application filed September 12, 1899. Serial No. 730,231. (No model.)

To all whom it may concern:

Be it known that I, WILLIAM EDWARD SEELYE, of Brainerd, in the county of Crow Wing and State of Minnesota, have invented 5 a new and Improved Combination-Tool, of which the following is a full, clear, and exact description.

The object of the invention is to provide a new and improved combination-tool, more especially designed for the use of hunters, timber-cruisers, explorers, &c., and combining a hunting-ax with a knife removable from the ax-handle to permit of using either the ax or the knife separately whenever desired.

15 The invention consists of novel features and parts and combinations of the same, as will be fully described hereinafter and then pointed out in the claims.

A practical embodiment of my invention is 20 represented in the accompanying drawings, forming a part of this specification, in which similar characters of reference indicate corresponding parts in all the views.

Figure 1 is a side elevation of the improvement with parts in section. Fig. 2 is a transverse section of the same on the line 2 2 in Fig. 1. Fig. 3 is a perspective view of the knife-spring, and Fig. 4 is a side elevation of the knife detached from the ax and with the 30 blade in an open position.

The improved combination-tool consists, essentially, of an ax A and a knife B, having a handle C, common to both, but made in sections C' C², of which the section C' is preferably integral with the ax-head A', and the section C² forms the handle or casing for the blade B' of the knife B. The blade B' is pivoted at the outer end of the section C² and is pressed on at its fulcrum end by the free end 40 of a spring D, secured to the section C² and formed at its fixed end with a collar D' and a reduced screw-rod D², screwing in an internal thread C³, formed in the outer end of the section C', a pin D³ extending from the said 45 screw-rod into a socket C⁴, likewise formed in the end of the section C'. Thus by turning the section C² the screw-rod D² readily screws into the outer end of the handle-section C', so that the section C² forms a continuation of the section C' to produce a complete ax-handle for the ax A; but when the section C² is removed the ax may also be used with

the handle-section C' as the handle only. The free end or point of the blade B' is adapted to engage a lined recess E in the outer end of 55 the section C', so that when the knife-section C² is in position on the section C' and the blade B' is closed then the section C² is locked against accidental unscrewing from the section C' by the point of the knife-blade B' engaging said 60 recess E. As shown in Fig. 3, the spring D, with the collar D', the screw-rod D², and pin D³ are formed of a single piece.

When the several parts are assembled, as shown in Fig. 1, the combination-tool may be 65 used as an ax in the usual manner or as a knife by opening the blade B'; but, as previously mentioned, the sections C' and C² may be disconnected from each other to permit of using the ax or the knife independent one of 70 the other.

Having thus fully described my invention, I claim as new and desire to secure by Letters Patent—

1. A combination-tool, comprising an ax 75 and a knife, with a handle common to both and made in sections removably connected with each other, one section being for the ax and the other for the knife, the blade of the knife when closed, serving to lock the sections against accidental disconnection, substantially as shown and described.

2. A combination-tool, comprising an ax and a knife, with a handle common to both and made in sections removably connected 85 with each other, one section being for the ax and the other for the knife, the sections being locked against accidental disconnection by the free end of the knife-blade, when the latter is in a closed position, substantially as 90 shown and described.

3. A combination-tool, comprising an ax and a knife, with a handle common to both and made in sections removably connected with each other by a rotary connection, one 95 section being for the ax and the other for the knife, the free end of the knife-blade being adapted to engage a recess in the ax-handle section to lock the knife against accidental disconnection from the ax, as set forth. 100

4. A combination-tool, comprising an ax-head, a knife-blade, an ax-handle, a knife-handle, a casing screwing in the end of the ax-handle, the knife-blade being adapted to

engage with its free end a lined recess in the ax-handle, substantially as shown and described.

5. The combination with the handle of an ax or the like, of a knife handle or casing removably connected with the ax-handle by a rotary connection and provided with a blade, the end of which is adapted to engage the end of the ax-handle to lock the parts together, substantially as described.

10. The combination with the handle of an ax or the like having a threaded socket and

a recess in its end, of a knife handle or casing provided at one end with a pivoted blade and at its other end with a screw-threaded 15 rod screwing into the socket of the ax-handle, the end of the blade of the knife normally engaging the recess of the ax-handle and locking the parts together, substantially as described.

WILLIAM EDWARD SEELYE.
